UNITED STATES PATENT OFFICE

147,631

DESIGN FOR A LADY'S HANDBAG OR SIMILAR ARTICLE

Robert Appel, New York, N. Y.

Application October 28, 1946, Serial No. 134,346

Term of patent 3½ years

(Cl. D87—2)

To all whom it may concern:

Be it known that I, Robert Appel, a citizen of the United States and residing at New York city, in the county and State of New York, have invented a new, original, and ornamental Design for a Lady's Handbag or Similar Article, of which the following is a specification, reference being had to the accompanying drawing, forming part thereof.

Fig. 1 is a front elevation of a lady's handbag or similar article, showing my new design.

Fig. 2 is a side view thereof.

Fig. 3 is a transverse sectional view taken on line 3—3 of Fig. 1.

Fig. 4 is a sectional view taken through line 4—4 of Fig. 1, and drawn to an enlarged scale.

The dominant feature of the design resides in the portions shown in full lines.

I claim:

The ornamental design for a lady's handbag or similar article, substantially as shown and described.

ROBERT APPEL.
